(57) **CLAIM**

The ornamental design for a set of drawer trays for medical and laboratory equipment, as shown and described.

DESCRIPTION

1.1 is a top perspective view of a set of drawer trays for medical and laboratory equipment;

1.2 is a front view thereof;

1.3 is a back view thereof;

1.4 is a top view thereof;

1.5 is a bottom view thereof;

1.6 is a left side view thereof; and

1.7 is a right side view thereof.

Elements drawn in broken lines are environmental features that form no part of the claimed design.
